UNITED STATES PATENT OFFICE.

EMMA I. WEBB, OF DENVER, COLORADO.

SKIRTED UNION SUIT.

1,007,995.

Specification of Letters Patent.

Patented Nov. 7, 1911.

Application filed May 25, 1911. Serial No. 629,457.

To all whom it may concern:

Be it known that I, EMMA I. WEBB, a citizen of the United States, residing at Denver, in the county of Denver and State of Colorado, have invented certain new and useful Improvements in Skirted Union Suits, of which the following is a specification.

My invention relates to skirted union suits.

- 10 The object of the invention is to provide a union suit in which the blouse has extending therefrom an integral drawers; the drawers extending at the seat portion down from the rear of the blouse and upwardly 15 at its front portion under the skirt of the blouse so that the front portion of the blouse forms an apron for the drawers. This object I accomplish by the construction shown in the accompanying drawing, in which—
20 Figure 1 is a front elevation of my improved union suit. Fig. 2 is a rear elevation thereof. Fig. 3 is a front elevation with the skirt turned up to show the drawers. Fig. 4 is a like view with the drawers' flap 25 opened. Fig. 5 is a plan of the blank from which the union suit is formed. Fig. 6 is a front elevation of a blouse and drawers for boys.

A, designates the blouse or apron, terminating at its front and sides in a skirt A', while the back A², of the blouse extends down below the lower edge of the skirt A', where it is folded upon itself to form the drawers B. At the ends of the folded portion of the material forming the drawers B, are formed the leg openings B'. The sides B² of the rear part of the drawers B, are folded around to the front, and their inwardly and upwardly converging edges are 40 provided with buttons b, or equivalent fastenings, while the correspondingly inclined edges b', of the front flap B⁴, of the drawers are provided with button holes b², or other equivalent fastening members. 45 These buttons and button holes b, b², extend down to the leg openings B' so that when the front flap B⁴, is unbuttoned the drawers as a whole may be laid out flat for ironing.

The material forming the back of the blouse A, is gathered at the waist line to take up the fullness and impart a neat finish at that point, while above the waist line the back of the blouse is provided with an opening A⁴, having buttons and button holes 55 a, a'. Apron strings a², are secured at their ends to the rear upper corners a³ of the skirt

A'. The garment is formed from a single length of material, see Fig. 5, folded upon itself at the shoulders of the blouse, cut out at its edges and stitched together along the under sides of the sleeves A⁵, and this stitching extends down to the waist line. Then the material is folded to form the drawers portions as above described. At the inner side of the back of the waist line is secured 65 a waist band C, the two ends of which extend thence to the upper corners of the side portions B², of the drawers, where they are secured, and the extremities of the band may be tied or buttoned together at the upper end of the front flap B⁴, thus relieving the upper buttons b, of the strain and holding the sides of the drawers in place when the front flap B⁴ is unbuttoned.

The style of blouse may be changed to 75 suit boys and girls; a boy's union suit being shown in Fig. 6. The suit may be made up as an infant creeper suit, girl's play suit and boy's blouse suit. The improved union suit may be readily made up as a bathing suit 80 also, if desired, still adhering to the main features of my construction.

It will be seen that the garment renders the dressing of children easy and expeditious and that the garment may be easily 85 laundered.

Any desired collars, cuffs and other ornamental trimmings may be employed.

What I claim is:

1. A skirted union garment comprising, 90 a blouse or apron, and a drawers, the latter formed from a length of material extending down from the waist line at the back of the apron to a point below the skirt and there folded upwardly upon itself to form the 95 front flap of the drawers; the sides of said length of material forming the back of the drawers being folded inwardly to meet the sides of said front flap, fastening devices for side edges of the drawers; the lowermost 100 fastenings closing the leg openings, and a waist band secured to the inner side of the back of the garment at the waist line, and also secured to the upper inner corners of the said inturned sides of the drawers, and 105 the extremities of said waist band being adapted to be secured together.

2. A skirted union garment comprising, 110 a blouse or apron, and a drawers formed from a single length of shaped material upon itself, and stitched together along the along the side edges of the body below the

arm holes to the waist line to form the apron or blouse, the material at the back extending down below the skirt of the apron or blouse and folded transversely and up under the front side of the skirt, and fastenings for the sides of the drawers thus formed; the lowermost fastenings closing the leg openings left at the ends of the transverse fold.

3. A skirted union garment comprising, a blouse or apron, and a drawers formed from a single length of shaped material, folded upon itself, and stitched together along the sleeves and body to the waist line to form the apron or blouse, the material at the back

extending down below the skirt of the apron or blouse and folded transversely and up under the front side of the skirt; the side meeting edges of the drawers being correspondingly inclined and provided with fastening devices; the lowermost fastenings closing the leg openings at the ends of the transverse folds.

In testimony whereof I affix my signature in presence of two witnesses.

EMMA I. WEBB.
